BARBECUE BASTER OR THE LIKE

Wilson K. Jones, 1812 Union St., and George N. Newham,
Rte. 2, Canal Road, both of Brunswick, Ga.

Filed July 12, 1961, Ser. No. 65,896

Term of patent 14 years

(Cl. D44—29)

FIG. 1 is a perspective view of a barbecue baster showing our new design;

FIG. 2 is a bottom plan view; and

FIG. 3 is an end elevational view as observed from the left-hand end of FIG. 1.

We claim:

The ornamental design for a barbecue baster or the like, as shown.
